GAME

Charles J. Danner, 15111 Appoline Ave., Detroit, Mich.
Filed Jan. 18, 1961, Ser. No. 83,526
9 Claims. (Cl. 273—93)

This invention relates to a game simulating a competitive sport such as baseball, to be played by at least two opposing players representing the opposing teams, in particular the pitcher and the batter, and who, similar to the actual competitive sport, attempt to outguess or outplay each other by electing certain specific actions in view of the condition of the competition, as for example, the condition of the bases, the number of "outs," the score, etc., with enough of an element of chance or "luck" involved so that the outcome or consequences of any selected action cannot always be predicted with complete certainty, but on the other hand will be in accordance with realistic probability.

The game is played utilizing a game device having a portion which may be termed a "bat" to be handled by the player representing the batter, and another portion which may be termed a "ball" or pitch device to be handled by the player representing the pitcher. The batter may swing at the ball attempting a hit, a sacrifice, etc. by placing his bat adjacent the ball and if properly placed, and he has guessed the type of pitch, i.e., a curve, a slider, etc. that the pitcher is delivering, the batter will hit the ball, the outcome of which will be reflected at a play indicator, and, as with the actual sport, will be dependent partially on chance, partially upon how well the ball is hit and upon the conditions of the bases. The batter may, for example, hit the ball to the shortstop who throws him out at first base; or he may hit it between the fielders for a single or a double; or there may be an error allowing him to get on base or take an extra base, etc. On the other hand, the batter may miss the ball during his swing. This is suitably indicated electrically as a strike. If the batter decides not to swing, by not placing the bat adjacent the ball, and the pitcher throws a strike, or a ball, each is suitably indicated.

The game device may include the representation of a playing field, such as a baseball diamond, across which game pieces may be moved by the players to keep track of base runners. The players exchange the bat and the ball after three "outs." The game may be played for nine innings, with extra innings to eliminate tie scores. Wherever possible the usual rules of the competitive sport being simulated are followed.

The principal object of the invention is the provision of a relatively inexpensive game device which may be played by two or more players to simulate a competitive sport, such as baseball, and which involves some element of chance as well as the ability of the players to outguess each other, and with which game they may enjoy the same rules and possible outcomes of their selected actions as is experienced by actually participating in the competitive sport being simulated.

This application is a continuation-in-part of application Serial No. 846,754, filed October 15, 1959.

Other objects, advantages and meritorious features will more fully appear from the specification, claims and accompanying drawings, wherein:

FIG. 1 is a side view through a game device embodying the invention showing the same resting upon a table or the like, with the right-hand end in section taken along line 1—1 of FIG. 2;

FIG. 2 is a top view of the device shown in FIG. 1;

FIG. 3 is a cross-sectional view taken on the line 3—3 of FIG. 2;

FIG. 4 shows, in part, a portion of the play indicating cylinder as it would be seen by the players through the

2

windows of the game device as well as the electric index for indicating which line of play notations on the cylinder is to be referred to;

FIG. 5 is a vertical cross-sectional view through the 5 upstanding panel or "plate" showing the plug and socket members, representing the ball and bat respectively, engaged on opposite sides of the panel;

FIG. 6 is a side view of the plug device;

FIG. 7 is a front view of the plug device;

FIG. 8 is a view of the bat device;

FIG. 9 is a view of the plug device looking in the direction of arrow 9 in FIG. 6;

FIG. 10 is a cross-sectional view through the plunger switch of the socket device;

FIG. 11 is a somewhat schematic view of the upstanding panel as it would be seen by one of the players, acting for example, in the role of pitcher, and will be occasionally referred to hereinafter as the "pitcher's side;"

FIG. 12 is a somewhat schematic view of the other 20 side of the upstanding panel as would be viewed by the opposing player, such as one acting in the role of batter, and will be occasionally referred to hereinafter as the "batter's side;"

FIG. 13 is a schematic representation of the electric 25 wiring diagram of the panel as it would be seen by the pitcher;

FIG. 14 is a schematic representation of a selector switch, hereinafter occasionally referred to as the "batter's selector's switch;" and

FIG. 15 is a schematic representation of a step-down 30 transformer for delivering electric current to the device, as well as two switches and the electric motor.

GENERAL ARRANGEMENT

Hereinafter the game will be described in connection with a simulated game of baseball, though it will become apparent to those skilled in the art as the description proceeds that the game may be adapted to simulate other competitive sports. It is contemplated that at least two players are required, though more than this number may be involved as desired. The two players are seated on opposite sides 30 and 32 of the game board 34, facing each other across the board and viewing opposite sides of the upstanding panel 36 simulating the "plate" or more particularly the area over home plate through which the pitcher throws the ball and through which the batter swings, as viewed by the player. The player at side 30, starts first as the batter, with the panel 36 disposed as shown in FIGS. 1 and 2. The player at side 32 starts as the pitcher. Their roles are reversed when three "outs" are made, by removing the upstanding panel 36 which is removably plugged at its lower edge into the board, reversing it, and replugging it into the board.

Connected to the batter's side 36a of the panel by electric leads 38 and 49 which may be wrapped together as a cable 42, are socket means which may be in the form of a baseball bat 46, which the player at side 30, acting in the role of batter, manipulates. Plug means which may be in the form of a ball 48, hereinafter sometimes 55 referred to as the pitch device, is connected by electric lead 50 to the other side, or pitcher's side 36b of the panel. The ball is manipulated by the player at side 32 acting in the role of pitcher. When the panel is reversed to reverse the roles of the players, the ball and bat are exchanged by the players.

The upper surface of the game board may be provided with the representation of a playing field, such as a baseball diamond 52 having a first base, a second base, and a third base as well as base lines, all according to conventional practice. Playing pieces simulating base runners, 60 not shown, may be provided which are moved by the players around the diamond to follow and indicate the

condition of the bases. At the right hand of the pitcher are means for indicating the outcome of various plays. Such means comprises a play indicating cylinder 102 visible through eight windows 54, 56, 58, 60, 62, 64, 66 and 68, each window corresponding to one of the possible eight conditions of the bases, i.e., from "bases empty" (window 68) to "bases loaded" (window 54).

Representations of the bases are provided above each window in the form of three circles arranged in triangular fashion and representing first, second, and third bases, with the circles containing the letters A, B, or C if a base or bases is occupied. Such representations are indicated by reference numerals corresponding to those identifying each window together with the suffix "a" as shown both in FIGS. 2 and 4. Thus, window 68 has three empty circles 68a indicating the bases are empty and the plays indicated on the cylinder and visible through such window are those appertaining to the game when the bases are empty.

The player in the role of pitcher and manipulating the ball 48 may selectively energize any one of four prongs 72, 74, 76 and 78 extending in parallel relation from a flat face 204 of the ball, by turning a first selector switch 80 incorporated in the pitch device, and hereinafter referred to as a pitch selector switch. The four positions of this switch are shown in FIG. 7 at A, B, C and D. By this switch the pitcher may select whether he will throw respectively a fast ball, a sinker, a curve, or a slider. After selecting the pitch he elects to throw he plugs the prongs of the pitch device into the panel 36.

Panel 36 has twenty-five holes indicated at 82, extending therethrough and arranged in a regular pattern with the nine centrally grouped holes circumscribed by a square 84 and representing the "strike" zone. The holes outside the square represent pitches other than over the "plate." The pitcher, in plugging in the pitch device, may select the area of the panel that he feels will best serve his purpose.

Adjacent each hole 82 and on the batter's side 36a of the panel is a spring contact 86 (see FIG. 5) which engages the projecting end of a prong of the pitch device to make electrical connection therewith. The contacts adjacent the holes in the strike zone enclosed by square 84 are serially wired to an electric indicator, such as a light bulb 88 at the upper edge of the panel above the word "strike" printed on opposite faces of the panel therebelow. The contacts outside of the strike zone are serially wired to a plunger switch in the bat 46. While a plunger switch in the bat is described herein, it will be understood that such switch may be a simple two-position switch mounted in any convenient location for manual operation by the player acting in the role of batter. The bat or socket 46 is provided with a pair of sockets 106 and 108 which are receivable over adjacent horizontally aligned projecting prongs of the pitch device. If the bat 46 is plugged on to the prongs projecting through the panel, and certain other conditions are fulfilled, then bulb 90 at the upper edge of the panel and also above the word "strike" will be illuminated. If the batter elects not to swing and therefore does not plug the bat over the prongs, the bulb 92 at the upper edge of panel 36 and above the word "ball" may be illuminated.

Once the pitcher has plugged the pitch device 48 into the panel and has adjusted the pitch selector switch 80 (either before or after the device has been plugged into the panel) he grasps the action switch 94, located at home plate on the diamond of the playing board, and turns it to position 1 shown in FIGS. 2 and 15. This causes an electric indicator such as a light bulb 96 disposed, for example, at the pitcher's mound, to be illuminated, indicating to the batter that the pitch is "on the way."

The batter then may either "swing," by plugging the bat device 46 over two of the prongs of the pitch device projecting through the plate or panel 36, or he may refrain from swinging in anticipation of a "ball." If he

elects to swing he places the bat over those two prongs (in a horizontal plane) according to where he expects the pitch to be with regard to the strike and non-strike zones of panel 36, or in other words whether he expects the pitch to be over the plate, inside or outside, high or low. Assuming the batter decides to "swing," he then turns the batter's selector switch 104, appearing on his side of panel 36, to either the "hit" position, or to the "sacrifice" position or to "steal" position if there are one or more runners on base. Then the batter turns the action switch 94 to the second position in the direction of the arrow in FIGS. 2 and 15. In so turning the action switch contact 98 is momentarily wiped, in turn momentarily energizing electric motor 100 and causing the play indicating cylinder 102 to spin beneath the windows 54-68. When the cylinder stops revolving the outcome of the play is indicated through the appropriate window as more fully described hereinafter.

At position number 2 of the action switch 94 a circuit is completed through the pitcher's selector switch 80 to energize one of the prongs of the ball. If that prong energized is in engagement with one of the contacts 86 on the batter's side of plate 36, either a "strike" or a "ball" will be registered by lights 88, 90 or 92, at the upper edge of the plate. If however the contact which would normally engage the energized prong is held out of contact by interposition of the bat device as shown in FIG. 5 for contact 86a, then none of lights 88, 90 or 92 will be illuminated and the action will be noted at the play indicating cylinder.

If the contact 86a is held away from the energized prong, the socket 106 or 108 in the bat device, whichever socket is received over the energized prong, will make electrical contact with the prong and, through the batter's selector switch 104, energize one of the electric indicators at the index 118 adjacent the play indicating cylinder. Such indicators preferably comprise a plurality of light bulbs 110, 112, 114 and 116 grouped in a column one above the other as shown in FIG. 4. Each of the bulbs is associated with a legend: "sacrifice," "light hit," "heavy hit," and "steal." By reference to the lighted bulb and reading laterally to that window which is to be associated with the condition of the bases at the time of the play, the players can determine the outcome of the play as hereinafter more particularly described.

Playing the game

Assuming that we are starting with the first batter at the commencement of the game, the pitcher takes up the "ball" and plugs into the panel 36 where he desires to deliver the ball in reference to the strike zone. With reference to FIG. 1, assuming he places the ball so that the prongs occupy holes 82a, 82b, 82c and 82d, he then turns pitcher's selector switch 80 to position C (see FIG. 7) to throw a "curve ball." Then he turns action switch 94 at "home plate" to position 1 causing bulb 96 to be lighted and indicating to the batter that the pitch is on the way. The batter may then choose to attempt a hit or may anticipate a ball and therefore not swing. If he chooses the latter he merely turns action switch 94 to position number 2. This will complete a circuit to light 92 indicating a "ball" as the prong energized lies outside of the strike zone.

The pitcher then turns the action switch 94 to the starting position and either pulls the ball 48 from the panel to reposition it, or leaves it in the same position and turns the pitcher's selector switch 80 to a new position. Assuming the pitcher selects a slider (position D), and does not remove the ball from the panel, this sets up prong 74 to be subsequently energized. The pitcher then turns the action switch 94 to position 1 indicating the pitch is on the way. The batter thereupon decides whether he will swing or not. Assuming he elects to swing, he places the bat device 46 such that the two sockets 106 and 108 are received over two of the four

prongs projecting through the panel. Assuming he positions the sockets over prongs 72 and 74, he then sets the batter's selector switch 104 to "hit" and turns the action switch 94 to position 2. This will complete a circuit through socket 106 of the bat and energize light bulb 112 at the index 118 which will register a "light hit" (see FIG. 4). Reading from "light hit" to the right across to the window 68, and assuming the play indicating selector has stopped spinning at the position shown in FIG. 4, the batter would observe "single 8" which would be interpreted to mean "batter singles to center field." The batter would then move a game piece to the first base position on the diamond, and play would be resumed along the lines above described. As nearly as possible the same rules used in the actual sport would be employed for scoring and otherwise playing the game.

Construction of game device

The game comprises a frame in the form of a hollow shallow box 150 which may rest upon any suitable support such as a table 151, with the top of the box providing the game board 34. The right-hand end of the box as viewed in FIGS. 1-3 is raised to provide a convex surface or cover 152 through which the windows 54-68 open exposing the play indicating cylinder 102 therebeneath. The cylinder is mounted on a shaft 154 carried at opposite ends by side walls 156 and 158 of the box. The cylinder is fixedly mounted on the shaft and is driven by electric motor 100 (see FIG. 3) through belt drive or the like 160. A peripherally notched wheel 162 rigidly mounted on the shaft cooperates with a spring-loaded detent 164 to stop the cylinder in any one of sixteen possible positions.

The surface of the cylinder exhibits eight axially spaced apart columns of lines of notations describing the outcome of various plays, one column for each of the windows

face of the cylinder in proper registration with notches in the wheel 162. The notations in each column comprise a code corresponding to the code conventionally in use by persons acquainted with the shorthand of keeping track of the progress of the competitive sport. A suitable table may be provided which may either form a part of the game device itself, or be separate therefrom, to enable players unacquainted with the code to interpret same. An example of the table is set forth hereinafter.

Each of the columns of notations is appropriate for describing the possible outcome of plays with the bases in the condition with which the window exposing the column is to be associated. As mentioned herebefore, each window is provided with three circles thereabove indicating the condition of the bases with which the window is to be associated. Furthermore, each line of notations exposed in each window is arranged to indicate the possible outcome of a play associated with either a "sacrifice," a "light hit," a "heavy hit," or a "steal." Therefore, in any one of the sixteen positions in which the cylinder may stop spinning, each window will expose four possible outcomes of the play, and each outcome will be associated with one of the indices of index 118. As a consequence, should the light 112 be illuminated with no runners on base, and with the cylinder stopped as shown in FIG. 4, the batter would read across horizontally to the window 68 and would there note "single 8" which would be interpreted as before-mentioned.

Set forth below is a table set up to correspond to the various plays coded in the columns and appearing in the windows with the cylinder in the position shown in FIG. 4. FIG. 4 has been schematically reproduced above the table to facilitate understanding the correspondency between the code on the cylinder and the table. It is to be understood that the following table shows only one-sixteenth of the possible plays appearing on the indicating cylinder.

④ ④ ④		○ ④ ○	④ ○ ○	○ ○ ④	○ ○ ○
Out 2-3; C out 3-2; B-3rd; A-2nd.	Sacrifice	Safe on 1st; C Scores	S.O.E. 2-4; B-3rd	Out 5-3; A-2nd	No play.
Out 7; C out 7-2; B-2nd; A-1st.	Light hit	Out 5; C-3rd	Out 1-3; B-2nd	Out 6; A-1st	Single 8.
Triple ABC Score	Heavy hit	Out 9; C Scores	Out 5-3; B-3rd	Double; A-3rd	Home run.
C Scores (B out); A-2nd. (2-5).	Steal	C out 1-2	B safe at 3rd	A out 2-4	No play.
Batter out, catcher to first; man on third out, 1st baseman to catcher; man on 2nd goes to 3rd; man on first to 2nd.		Batter bunts and is safe at first; man on 3rd scores.	Batter bunts, is safe when 2nd baseman drops throw from catcher; man on 2nd goes to 3rd.	Out, 3rd to 1st; man on 1st advances to 2nd.	No base runners, a sacrifice is not possible.
Fly out to left field. Man on 3rd out 1.fld. to catch; men on 2nd and 1st do not advance.		Fly out to 3rd baseman. Runner on 3rd remains.	Out, pitcher to 1st. Runner remains on 2nd.	Fly out to shortstop; man on 1st remains.	Batter singles to center field.
Batter hits triple; men on first, second and third score.		Fly out to rt. field; man on 3rd scores.	Out, 3rd baseman to 1st; man on 2nd goes to 3rd.	Batter gets a double; man on 1st goes to 3rd.	Home run hit by the batter.
Man on 3rd scores; man on 1st steals 2nd; man on 2nd out, catcher to 3rd baseman.		Man on 3rd attempts to steal home, is out, pitcher to catcher.	Man on 2nd base steals third.	Man on 1st is out stealing 2nd, catcher to 2nd baseman.	No base runners, a steal is not possible.

CODE

A—Man on First; B—Man on Second; C—Man on Third.
1—Pitcher; 2—Catcher; 3—First Baseman; 4—Second Baseman; 5—Third Baseman; 6—Shortstop; 7—Left Fielder; 8—Center Fielder; 9—Right Fielder.

dows 54-68. The lines of notation, as shown in FIG. 4, are peripherally spaced such that four lines will be exposed in each of the windows at each of the sixteen possible positions at which the cylinder may stop rotating. As there are sixteen possible positions at which the cylinder may stop rotating, and there are four lines of notation for each possible position, sixty-four lines of notation will comprise each column. The columns may be exhibited in any suitable fashion, such as being printed on paper which is thereafter wrapped about the sur-

At the left end of the game board as viewed in FIGS. 1 and 2, it is provided with ten electric sockets as shown in FIGS. 11 and 12, which open upwardly to receive ten cooperating prongs extending downwardly from the lower edge of panel 36. The prongs and sockets are arranged in two groups of five each. One group are dummy prongs serving only for the purpose of mechanically stabilizing and anchoring the panel in an upright position to the game board. The other set of five prongs are electrically connected to conductors within or on the faces of the panel

36. The conductors are connected to the sockets and extend within the shallow box 150 as schematically indicated in FIGS. 11 and 12. When the panel 36 is plugged into the sockets in the game board, the prongs and sockets, schematically shown at 166a, 168a, 170a, 172a, and 174a in FIGS. 13, 14 and 15 complete electric circuits in corresponding conductors 166, 168, 170, 172 and 174.

The panel 36 is formed of electrically non-conductive material. The conductors 166, 168, 170, 172 and 174 extend through it or are disposed on it in any suitable fashion. The contacts 86, which are formed of an electrically conductive spring material, are secured to the batter's side 36a of the panel in any suitable fashion. Each contact is generally J-shaped as shown, with the lower end adapted to engage the prongs 72, 74, 76 and 78 of the ball 48 to make electric contact therewith, as shown by prong 78 in FIG. 5. Suitable conductors serially connect contacts 82 as schematically shown in FIG. 13, to provide nine contacts in the "strike" area which connect with the bulb 88. The remaining contacts 82 are serially connected by conductor 182 with a plunger switch in the bat 46 as shown in FIGS. 10 and 13. The plunger switch will automatically determine whether the bulb 90 or 92 is energized depending upon whether the batter "swings" by plugging his bat to the prongs projecting through the panel from the pitch device or ball, or whether the batter does not swing anticipating a ball and therefore does not plug in the bat. The switch is provided with an electrically conductive plunger 184 having non-conductive ferrule 186 thereon, with the plunger tensioned outwardly by an electrically conductive spring 188 to which conductor 182 is connected. Any suitable means may be provided for limiting the outward projection of the plunger. At the outermost projected position of the plunger, ring 186 covers an electrically conductive ferrule 190 disposed in a groove in the bat and connected to conductor 192, preventing an electric circuit through the plunger between conductors 182 and 192. However, the plunger bears against electrically conductive ferrule 194 disposed in a suitably provided groove in the bat and to which ferrule 40 lead 196 is connected, thereby establishing a circuit between lead 182 and 196. When the bat is plugged on the prongs of the ball, the plunger is pushed inwardly and an electric circuit between conductors 182 and 192 established, and the connection between conductors 182 and 45 196 broken, as shown in FIG. 10.

The bat device 46 may, if desired, be shaped to represent a baseball bat or a portion thereof, and is formed of electrically non-conductive material. The electrically conductive sockets therein, 106, and 108, are connected to the batter's switch 104 by insulated electric leads 38 and 40 heretofore mentioned, which may be wrapped together as a cable 42. The pitch device 48 may, if desired, be shaped as a ball, having however a flat face 204 to about and overlie the face 36b of the panel as shown in FIG. 5. Device 48 is formed of electrically non-conductive material and switch 80 is disposed in the device. The switch may be of conventional rotary switch design having four stationary contacts and a moving contact as schematically shown in FIG. 15; the four stationary contacts being indicated at A, B, C, and D. The stationary contacts are connected to the prongs 72, 74, 76, and 78 as shown in FIG. 15. Movable contact 206 of the switch is adapted to be turned to selectively complete a circuit between conductor 166 to any one of the 65 prongs.

The bat device may be placed over the prongs so that the handle end 210 faces either to the right or to the left and in this fashion the player acting in the role of batter may be alternatively either a right-hand or a left-hand batter. The pitcher may also simulate either a right-hander or a left-hander by rotating the ball 180 degrees.

A conventional electric cord 270 shown in FIGS. 1, 2 and 15 may be plugged into a convenient electric outlet 75

(not shown) to deliver current to a step-down transformer 272 and from thence to the action switch 94.

What is claimed is:

1. In a game device for simulating a competitive sport: a member having a surface exhibiting a plurality of possible plays for determining the progress of the game, an upstanding panel having a plurality of holes extending therethrough from one face to the opposite face thereof, a plug device for removable juxtaposition on one face of the panel and provided with a plurality of electrically conductive prongs extendable through the holes in the panel when the plug device is juxtaposed on the panel, means for selectively energizing individual prongs, a socket device having a lesser number of electrically conductive sockets than the number of prongs on the plug device with the sockets receivable in electrically conductive relation over the projecting ends of individual prongs when the socket device is juxtaposed on the opposite face of the panel from the plug device, indicating means disposed adjacent said surface of the member for indicating the plays to be read thereon and including electrically operated indicators, and an electric circuit connected to said sockets and selectively connectable with the indicators for selective energization of the indicating means when a socket is received over an energized prong.

2. The invention as defined in claim 1 characterized in that said indicators comprise a plurality of light bulbs and said electric circuit is connected to each bulb and includes a selector switch for selectively connecting one bulb to each socket.

3. The invention as defined in claim 1 characterized in that said member is rotatably mounted and said indicating means disposed adjacent the surface of the member includes portions overlying said surface and allowing exposure of a predetermined area thereof, said indicating means further including a plurality of light bulbs disposed in registry with possible plays on the surface of said member exposed to view, and said electric circuit is connected to said bulbs and selectively operable to connect an individual bulb with an individual socket.

4. A game device for simulating a competitive sport comprising, in combination: a frame, a member rotatably mounted on the frame, a plurality of notations on the surface of the rotatable member indicating the outcome of various plays, a panel upstanding from the frame and having a plurality of holes extending therethrough from one face to the opposite face thereof, a plug device having at least two electrically conductive prongs extendable through the holes in the panel when the plug device is juxtaposed on one face of the panel, socket means having two electrically conductive sockets receivable over the projecting ends of two prongs when the socket means are juxtaposed on the opposite face of the panel, shiftable electric contact means on the panel for electrically engaging the prongs, said socket means having a portion for engaging and shifting said contact means on the panel out of electrical engagement with the prongs over which the sockets are received, an electric indicator connected to said contact means to be energized upon completion of a circuit by engagement of an energized prong with said contact means, first selector means for selectively energizing one of said prongs, two electric indicators disposed adjacent said surface of the rotatable member for indicating which notations thereon are to be referred to during play of the game, and electric circuit means connecting each of said two electric indicators to one of said sockets.

5. A game device for simulating a competitive sport comprising, in combination: a frame, a member rotatably mounted on the frame, a plurality of notations on the surface of the rotatable member indicating the outcome of various plays, a panel upstanding from the frame and having a plurality of holes extending therethrough from one face to the opposite face thereof, a plug device having at least two electrically conductive prongs extend-

able through the holes in the panel when the plug device is juxtaposed on one face of the panel, socket means having at least one electrically conductive socket receivable over the projecting end of one of the prongs when the socket means are juxtaposed on the opposite face of the panel, shiftable electric contact means on the panel for electrically engaging the prongs, said socket means having a portion for engaging and shifting said contact means on the panel out of electrical engagement with a prong over which the socket is received, an electric indicator connected to said contact means to be energized upon completion of a circuit by engagement of an energized prong with said contact means, first selector means for selectively energizing one of said prongs, a plurality of electric indicators adjacent said surface of the rotatable member for indicating which notations thereon are to be referred to during playing of the game, and second selector means electrically connected with said socket and operable to selectively electrically connect the socket with one of said plurality of indicators.

6. In a game device for simulating a competitive sport: a member having a surface exhibiting a plurality of possible plays for determining the progress of the game, an upstanding panel having a plurality of holes extending therethrough from one face to the opposite face thereof, a plug device for removable juxtaposition on one face of the panel and provided with a plurality of electrically conductive prongs extendable through the holes in the panel when the plug device is juxtaposed on the face of the panel, means for selectively energizing individual prongs, a socket device having a lesser number of electrically conductive sockets than the number of prongs on the plug device with the sockets receivable in electrical connection over the projecting ends of the prongs when the socket device is juxtaposed on the opposite face of the panel, at least two electric indicators disposed adjacent said surface of the member for indicating which possible plays thereon are to be referred to during playing of the game, electric circuit means for connecting said sockets selectively to each indicator, shiftable electric contact means on the panel for electrically engaging the prongs, means on said socket device for engaging and shifting said contact means out of electrical engagement with a prong over which a socket is received, and an electric indicator connected to said contact means to be energized upon completion of a circuit by engagement of an energized prong with said contact means.

7. A game device for use by at least two players for simulating a competitive sport comprising, in combination: a game board having on its upper surface the representation of a playing field upon which the competitive sport is played and across which playing pieces may be moved to keep track of the location of simulated players during playing of the game, a cylinder rotatably mounted on the board at one edge thereof and having a plurality of axially spaced apart peripheral columns of lines of notations upon its surface indicating the outcome of various plays, means cooperating with the cylinder for stopping its rotation at any one of a variety of positions to expose to view a plurality of lines of notations in each column, means on the board adjacent the cylinder in registry with each column and indicative of which column is to be used in accordance with the location of game pieces on the playing field, electric plug means for manipulation by one player and having a plurality of prongs, electric socket means for manipulation by another player and having at least one socket cooperable with a prong of the plug means to establish an electric circuit therebetween, a panel upstanding from the board and provided with a plurality of holes therethrough and through which the prongs of the plug means may be extended to project beyond the opposite face of the panel with the socket receivable over the projecting end of one

of the prongs, a first selector switch electrically connected to said prongs to be manipulated by one player to selectively energize one of the prongs, a plurality of electric indicators arranged adjacent the periphery of the cylinder in lateral registry with the lines of the columns of notation exposed to view when the cylinder stops rotating for indicating which lines are to be utilized in playing the game, a second selector switch connected to said socket and to said electric indicators for manipulation by the opposing player for selectively setting up a circuit to energize one of the indicators, electric contacts on the panel adjacent the holes therethrough to engage the prongs projecting through the holes to establish an electric circuit therewith, said socket means having a portion for shifting a contact on the panel out of engagement with a prong over the projecting end of which the socket is received, an electric indicator connected to said contacts to be energized upon completion of the circuit by engagement of an energized prong with a contact, and an action switch connected to the first selector switch and to a source of electric current to be manipulated by one of the players to deliver current to the first selector switch after the prongs of the plug have been extended through the panel and the socket connected to one of the prongs and the first selector and second selector switches have been manipulated as desired by the players.

8. The invention as defined in claim 7 characterized in that said panel is removably mounted on the game board.

9. A game device for use by at least two players for simulating a competitive sport comprising, in combination: a shallow box closed at its sides and top with the upper surface of the top being generally flat and exhibiting the representation of a playing field upon which the competitive sport is played and across which playing pieces may be moved to keep track of the location of simulated players during playing of the game, a cylinder rotatably mounted upon and between the side walls of the box adjacent one end of the box and having a plurality of axially spaced apart peripheral columns of lines of notations upon its surface indicating the outcome of various plays, said shallow box having a wall portion extending over the cylinder and provided with openings therethrough in registry with each column of lines of notations and exposing a determined number of plays in each column, means cooperating with the cylinder for stopping its rotation at any one of a variety of positions to expose to view through said openings said determined number of plays in each column, means on said wall portion adjacent each opening and indicative of which opening is to be used in referring to the columns of the cylinder in accordance with the location of game pieces on the playing field, motor means drivingly connected with said cylinder for spinning the same, electric plug means for manipulation by one player and having a plurality of prongs, electric socket means for manipulation by another player and having at least one socket cooperable with a prong of the plug means to establish an electric circuit therebetween, a panel upstanding from the box at one end thereof and provided with a plurality of holes therethrough and through which the prongs of the plug means may be extended to project beyond the opposite face of the panel with the socket receivable over the projecting end of one of the prongs, a first selector switch electrically connected to said prongs to be manipulated by one player to selectively energize one of the prongs, a plurality of electric indicators mounted on said wall portion adjacent said openings therethrough and in lateral registration with each of the possible plays exposed to view through said openings for indicating which plays are to be utilized in playing the game, a second selector switch connected to said socket and to said electric indicators for manipulation by the opposing player for selectively setting up a circuit to energize one of the indicators, electric contacts on the panel adjacent the holes therethrough to engage the prongs

11

projecting through the holes to establish an electric circuit therewith, said socket means having a portion for shifting a contact on the panel out of engagement with a prong over the projecting end of which a socket is received, an electric indicator connected to said contacts to be energized upon completion of the circuit by engagement of an energized prong with a contact, and an action switch connected to the first selector switch and to a source of electric current and to said electric motor to be manipulated by one of the players to deliver current to the first

selector switch and momentarily energize the motor after the prongs of the plug have been extended through the panel and the socket connected to one of the prongs and the first selector and second selector switches have been manipulated as desired by the players.
